UNITED STATES PATENT OFFICE.

HANS GEORG KÜSSNER, OF GRUNAU, GERMANY.

COUNTERPISTON MOTOR.

Application filed April 5, 1928, Serial No. 267,617, and in Germany April 4, 1927.

Numerous proposals relating to counter-piston motors have already been made, and motors of this type with open cylinder liners have become known, the pistons of which either turn each a shaft pertaining solely to it, there being, therefore, two shafts which are located at the ends of said liners, or the pistons of which turn one shaft in common with the aid of rods and oscillating levers, 10 that one shaft being either at one end of the motor, as in the German Patent 287,367, or being arranged laterally from, and parallel to the axis of, the motor, as in the British Patent 97/1900. The proposal also has been 15 made to arrange that one shaft in the middle of the cylinder enclosing the two pistons, viz., in a separate recess provided in the cylinder for that purpose, as is the case in the British Patent 3,720/1900.

20 All these known motors suffer from the drawback that they are too heavy and require too much space and are, therefore, not suited for light vehicles, such as motor cars and flying machines. The object of the present invention is to do away with those drawbacks, and I attain the purpose in view by the new arrangement and combination of parts shown 25 diagrammatically and by way of example on the accompanying drawing on which Figure 1 is a longitudinal section through a counter-piston motor designed according to this invention, Figure 2 is another longitudinal section on the plane A—B of Fig. 1, and Figure 3 is a cross-section in the plane C—D of Fig. 1. 30 Figure 4 is an enlarged fragmentary sectional view of the sectional shaft and radial interlocking bolts, and Figure 5 is a transverse sectional view of the shaft on line I—K of Figure 4.

35 On the drawing, z denotes a cylinder liner which is open at both ends and in which are enclosed four pistons a , b , c , d , of which a and c , as well as b and d , are rigidly connected with one another. The pistons forming a 40 pair are connected with each other by two rods k , or l respectively, and there are, thus, four piston rods. The cross sectional shape of each of these rods may be a quadrant of a circle and the four rods may be so arranged 45 with respect to each other as to form a complete circular sectional rod. The rods connecting the pistons a and c diametrically opposite to each other and pass through stuffing boxes e provided in the piston b and being 50 formed in the usual conventional manner. In

the same manner the rods pertaining to the pistons b and d pass through stuffing boxes provided in the piston c . All piston rods are bored through axially to provide passages f (Fig. 3) and are supplied with cooling oil for 60 the piston through extensible pipes f sliding in said passages.

The open liner or cylinder is provided with four rows of slots s which are open in the dead-centre position of the pistons, as shown 65 in Fig. 2, and serve in known manner for the escape of the combustion residues and for the entrance of the scavenging air.

The motor is a two-stroke cycle motor. There are three working spaces in each cylinder and the entire length of the liner is used 70 as combustion space. There is only active material in this motor.

To the outer pistons a and d are attached crosshead beams q , to each of which are pivoted four connecting rods p which turn by means of eccentrics two shafts w supported laterally from the cylinder only slightly remote from the axis of the same, as shown in Fig. 1. The eccentrics run on anti-friction 75 balls in their appertaining rings and their dimension in axial direction is so moderate that they all can move past one another. Much space is saved by this provision, and a closed power-transmitting path is established from 80 the pistons over the crosshead beams and the connecting rods to the shaft, and neither the motor casing is, nor the cylinders are, subject to a strain worth mentioning. The motor casing can, therefore, be very light. The connecting rods are subjected to tensile strain by 85 the ignition pressures of two of the working spaces, as appears from the lower part of Fig. 2, but are subjected to compressive strain only 90 by the pressure of one of the working spaces, as appears from the upper part of Fig. 2. As 95 the tensile strength is always greater than the compressive strength the material of the connecting rods is utilized in a very favorable manner.

100 The eccentric-bearing shafts w consist of as many sections as the motor has cylinders, and these sections are coupled with each other by radial bolts located in the joints between said sections. A common bolt m located in 105 the axis of the shaft sections keeps them all together whereby they are securely and reliably connected with each other.

The shafts bearing the eccentrics carry 110 also, at their ends, as well as in the middle,

equally large cog-wheels r which mesh with each other and turn both shafts with uniform speed.

I claim:

- 5 1. In an engine of the class described, a cylinder, a pair of parallel shafts laterally disposed adjacent to the cylinder and on opposite sides thereof and substantially equidistant therefrom, eccentric driving discs arranged on said shafts in pairs, the discs of each pair being disposed in an opposing relation to each other at opposite sides of the axis of their shaft, opposing pistons within the cylinder, eccentric driving rod connections between the pistons, and eccentric discs and driving connections between said shafts to maintain a fixed driving relation therebetween.

- 20 2. In an engine of the class described, a cylinder, a pair of shafts equidistantly disposed adjacent said cylinder at opposite sides thereof, driving connections between said shafts, pairs of opposed eccentric driving discs fixed to said shafts in opposing relation to each other, the eccentric of one pair on one shaft being in the same plane as the opposing eccentric of another pair on the other shaft, and operative connections between the pistons and the eccentrics whereby the driving forces from the pistons are delivered to the shafts in opposite directions at substantially opposite points equidistant from the axes of the shafts.

- 35 3. In an engine of the class described, a cylinder open at its opposite ends, opposing pistons within said cylinder, a pair of shafts disposed laterally with respect to the axis of the cylinder, said shafts being composed of a plurality of complementary interlocking sections, securing means for holding said shaft sections together, pairs of oppositely disposed eccentric driving members secured to said shaft sections, the eccentrics of each pair on one shaft being disposed in the same plane as the opposing eccentrics on the other shaft, and driving connections between the pistons and said eccentrics.

- 50 4. In an engine of the class described, a plurality of driving units, each unit consisting of a cylinder, a pair of laterally disposed parallel shafts arranged adjacent the cylinder at opposite sides thereof, two pairs of opposing driving eccentrics arranged on each shaft at opposite sides of the cylinder, the eccentrics of each pair being arranged in opposition relation to each other, pistons within the cylinders, crossheads connected to the pistons, and a pair of connecting members between the crossheads and each group of eccentrics.

- 55 5. In an engine of the class described, a cylinder, groups of pistons within the cylinder, sectional shafts connecting the alternate pistons of the group together, crossheads for the exterior pistons of the group, a laterally

disposed shaft adjacent the cylinder, a pair of opposed eccentric members on the shaft on each side of the cylinder, and connecting members between the crossheads and the eccentric members whereby the force from the pistons will be delivered to the shaft in opposing directions at opposite sides of the axis.

60 6. In an engine of the class described, a cylinder, a pair of laterally disposed intergeared parallel shafts adjacent said cylinders, supporting means for the shafts and cylinder, groups of pistons within the cylinder, axially located sectional piston rods connecting the alternate pistons of the group together, a pair of opposed eccentric members disposed on each shaft on each side of the cylinder, the eccentrics of one pair on one shaft on one side of the cylinder being in the same plane as the opposing eccentrics on the other shaft on the same side of the cylinder, and driving connections between the outside pistons of the group and the eccentrics whereby the forces from the pistons will be delivered to the shaft in opposite directions on opposite sides of its axis.

65 7. In a counter-piston motor, a combination of cylinders, pistons therein, a pair of intergeared eccentric bearing shafts arranged equally remote from the cylinder axis laterally and intermediate the ends of the cylinder, each of said shafts consisting of a plurality of sections, radial bolts for establishing driving relations between the sections, an axially arranged bolt extending through the sections to secure them together, and means for transmitting power from the pistons to the shafts.

8. In a counter-piston motor, a combination of cylinders, pistons therein, a pair of intergeared eccentric bearing shafts arranged equally remote from the cylinder axis laterally and intermediate the ends of the cylinder, each of said shafts consisting of a plurality of sections, radial bolts for establishing driving relations between the sections, an axially arranged bolt extending through the sections to secure them together, and means for transmitting power from the pistons to the shafts, in opposite directions at opposite sides of the axes of said shafts.

9. In a counter-piston motor, a cylinder open at both ends, four pistons therein, axially arranged piston rods connecting the first and third pistons and the second and fourth pistons together, said pistons forming three working spaces, ports through the cylinder to admit an explosive mixture to the working spaces, exhaust ports for discharging the spent gases from the working spaces, crossheads for the first and fourth pistons, a pair of laterally disposed shafts adjacent the cylinder and intermediate the ends thereof, a pair of opposing driving eccentrics on each shaft on each side of the cylinder, one

eccentric of each pair being in the same plane with the opposing eccentric of a pair on the other shaft, and connecting means between the crossheads and the eccentrics for delivering power in opposite directions to the opposing eccentrics whereby all the forces except the turning force to the shafts are substantially neutralized.

10. In an engine of the class described, an open ended cylinder, pistons within the cylinder working in opposite directions, means for admitting gases to the cylinder, means for exhausting the gases from the cylinder, a shaft transversely arranged adjacent the cylinder intermediate the ends thereof, a pair of eccentric members arranged on said shaft in opposing relation, and driving means between each of the pistons and one of the eccentrics whereby the driving forces are transmitted equally to the shaft in opposite directions on opposite sides of the longitudinal axis thereof to effect the neutralization of lateral forces on the shaft.

11. In an engine of the class described, a cylinder, a pair of opposed working pistons therein, crosshead connections to the pistons, transverse shafts arranged adjacent the cylinder at opposite sides thereof, and opposing driving connections between the crossheads on said shafts whereby the forces from the pistons will be delivered to the shafts in opposite directions at points substantially equidistant from the axes of said shafts and on opposite sides thereof.

12. In an engine of the class described, cylinders, opposed pistons within said cylinders, laterally disposed sectional shafts arranged adjacent the cylinders and intermediate the ends thereof, each section including two pairs of oppositely disposed eccentric driving members adapted when in position to lie on either side of the cylinders, connecting members between the pistons and the driving members whereby the forces from the opposing pistons within the cylinders are thereby delivered to the shaft in opposite directions on opposite sides of the axis thereof to neutralize any lateral stresses on the shafts, and interlocking connections between the sections of the shafts.

13. In an engine of the class described, cylinders, opposing pistons within the cylinders, a plurality of shafts operatively connected to certain of said pistons and slidably through other of said pistons, the shafts together forming a segmental cylindrical shaft located axially within the cylinder and pis-

tons, a sectional driving shaft arranged adjacent the cylinders laterally thereof, each of the sections of the shaft comprising a hollow shaft carrying two pairs of opposing eccentrics, each pair being disposed at opposite sides of a cylinder, driving connections between the pistons and the eccentrics whereby the opposing forces from the pistons will be delivered to the shafts in opposite directions at opposite sides of the axes thereof, interlocking connections between the shaft sections, and a common tie bolt extending through the hollow portions to secure the sections together.

14. In an opposed engine of the class described, a cylinder, opposing pistons within the cylinder, a sectional shaft, eccentric driving members arranged on the shaft in opposing relation, driving connections between the pistons and the driving members whereby the opposing forces from the pistons will be delivered to the shaft in opposing directions at opposite sides of the axis of the shaft, said shaft being composed of a plurality of hollow complementary sections, interlocking radial bolts between each of the sections, and a common tie bolt for securing all of the sections together occupying the hollow spaces in the sections.

15. In a counter-piston motor, a cylinder, opposed pistons within the cylinder, a shaft laterally disposed adjacent the cylinder intermediate of the ends thereof, opposed eccentric members secured on said shaft, driving connections between the pistons and the eccentrics whereby the opposed forces from the pistons will be delivered to the shaft in opposite directions on opposite sides of the shaft to neutralize lateral stresses on the shafts, and anti-friction bearing members between the driving members and the eccentrics.

16. In an opposed engine of the class described, a casing, a cylinder carried thereby, said cylinder having a plurality of opposed working pistons therein, a pair of laterally disposed shafts arranged in the casing adjacent the cylinder intermediate its ends, each of said shafts being provided with a pair of opposed driving eccentric members, and driving connections between the pistons and the eccentric members whereby the stresses from the pistons will be delivered to the shafts in points equidistant from and at opposite sides of their axis.

In testimony whereof I affix my signature.

HANS GEORG KÜSSNER.
